United States Patent Office

Des. 205,369

Patented July 26, 1966

205,369

ICE BUCKET

Howard W. Phillips, Nashville, Tenn., assignor to Aladdin Industries, Incorporated, Chicago, Ill., a corporation of Illinois

Filed Aug. 13, 1965, Ser. No. 86,574

Term of patent 14 years

(Cl. D44—15)

Fig. 1

Fig. 2

Fig. 3

FIG. 1 is a front elevational view of an ice bucket showing my new design,

FIG. 2 is a side elevational view thereof, and

FIG. 3 is a top view thereof.

I claim:

The ornamental design for an ice bucket, substantially as shown.
